CUP AND PLATE RACK

Hangwind F. Lippisch, Wooster, Ohio, assignor to Rubbermaid Incorporated, Wooster, Ohio, a corporation of Ohio

Filed Aug. 18, 1965, Ser. No. 86,628

Term of patent 14 years

(Cl. D44—29)

FIG. 1

FIG. 2

FIG. 4

FIG. 1 is a perspective view of a cup and plate rack showing my new design;

FIG. 2 is a top plan view thereof;

FIG. 3 is a side elevational view; and

FIG. 4 is a bottom plan view of the base member.

I claim:

The ornamental design for a cup and plate rack, as shown.
